(57) **CLAIM**

I claim the ornamental design for a flexible instrument stand, as shown and described.

DESCRIPTION

FIG. 1 shows a perspective view of an embodiment of the invention supporting an electric guitar.

FIG. 2 is a front view of an embodiment of the invention.

FIG. 3 is a side view of an embodiment of the invention.

FIG. 4 is a top view of an embodiment of the invention.

FIG. 5 is a perspective view of an embodiment of the invention; and,

FIG. 6 shows an embodiment of the invention in a second product configuration, which fits inside a case for an electric guitar.

The broken lines in FIGS. 1 and 6 illustrate the environment of the design and form no part of the claimed design.
